UNITED STATES PATENT OFFICE.

CARL MARCH, OF CHICAGO, ILLINOIS.

CASE.

Application filed July 21, 1926. Serial No. 124,037.

This invention has reference to a combination pocket case or folder which may be employed for holding cigars, matches, memorandum sheets, a calendar and other items.

5 The object of the invention is to produce a case for this purpose in which the outer or cover members may be formed of a strip of leather or other suitable pliable material, the same being folded transversely at 10 points equidistant from the center thereof, and the said central portion being engaged by a metal member that also provides a means whereby partition or division strips may be secured in the case, said strips on 15 the inner faces of the cover carrying compartments for cards, cigars, matches and other desirable items, and wherein the case may be easily swung to open position to disclose all of the compartments therein, there 20 being means for effectively clasping the case when in closed position.

To the attainment of the above broadly stated objects and others which will present themselves as the nature of the invention is 25 better understood, the improvement resides in certain other novel features of construction, combination and operative association of parts, a satisfactory embodiment of which is disclosed by the accompanying drawings.

30 In the drawings:

Figure 1 is a perspective view of a case in accordance with this invention, the same being in open position.

Figure 2 is an end view thereof with the 35 case closed.

Figure 3 is a detail longitudinal sectional view through the back of the case and through the reinforcing and cover spacing plate that is arranged on the back.

40 Figure 4 is a plan view showing the division sheets in the case swung to disclose devices carried by the case.

Figure 5 is a detail perspective view to 45 illustrate a slightly modified means of associating the cover members of the case and the division sheets or partitions therein.

Figure 6 is a perspective view to illustrate a manner in which the cover members of the case may be clasped together.

50 Figure 7 is a fragmentary perspective view to illustrate another means whereby the cover members may be separated from each other, and partition strips clamped between the cover members.

55 The outer member of my improved case is made from a single strip of suitable

strong flexible material, comparatively stiff leather preferred. This strip or sheet is bent transversely upon itself at points equidistant from the center thereof, and by so bending the strip I provide the same with the covers 1 and 2 and with the back 3. The back is reinforced by a metal plate 4, the plate being of a width equaling that of the back. This plate has its ends bent under the back, as at 5. In this manner it will be noted that the back is materially reinforced and the plate may be of any desired metal and may be ornamented or provided with the monogram of the owner as 60 disclosed by Figure 1 of the drawings. Of course, the plate need not be provided with the portions 5 as disclosed by Figure 3, but the confronting ends of the under portions of the plate may be brought to contact with 65 each other, and if desired, may be soldered or otherwise connected. Both of the back members 1 and 2 have their outer edges reinforced by metal frames 6 and 7, respectively, the said frames being riveted or 70 otherwise secured to the back members. In the showing of Figures 1 and 2, the corners of these frames are flanged inwardly, the central portions thereof are bent against the inner faces of the back members 1 and 2 and 75 riveted thereto, but in the showing of Figure 6 the frames 9 and 10 are U-shaped in cross section to snugly receive the back members therein. The edges of the frames 9 and 10 are cut to ornament the same and 80 one or both of the frames may have its outer plate provided with a central enlarged portion 11 on which is inscribed the monogram of the owner of the case. In the showing of Figures 1 to 4 no means is provided for 85 clamping the covers when the case is closed, but in Figure 6 the frame member 9 has a pivoted catch member 12 having a hooked end to engage with a depression or opening in the frame member 10.

100 In Figure 5 the ends of the plate 14 that reinforces the back of the case are rounded inwardly, as at 14, while in Figure 7 the plate 15 has on its corners knuckles aligning with other knuckles formed on hinge members 16 that are secured to the back members of the case. The hinge members have stop lugs 17 to contact with the plate 15 to hold the covers at right angles with respect to the back when the case is closed.

105 In Figures 1 and 2 I have stitched or otherwise fixed at spaced intervals on the in-

ner face of the back 2 of the case, a sheet of suitable material 18, the parts of the sheet, between the connected portions thereof being rolled to provide pockets for cigars.

5 The pockets 19 are gradually tapered from the top to the bottom ends thereof so that the cigars will be firmly gripped while arranged therein while at the same time the 10 cigars may be easily removed from the pockets.

The metal reinforcing plates or strips for the back of the case perform another and very important function. The plates are designed to engage with and compress 15 against the back of the case sheets or strips that provide partitions 20, and these partitions may be provided with any desired number of compartments, such as a card carrying compartment 21, a compartment or a 20 holder for a calendar 22, a compartment or a holder for a memorandum pad 23, together with a looped strap 24 for a writing implement 25 and the ends of a strap 26 for a match case 27. The partition strips 20 may 25 be disposed over the inner face of either of the covers 1 or 2, and the simplicity of my construction, the cheapness at which it may

be manufactured and the many advantages thereof, will, it is thought, be perfectly apparent to those skilled in the art to which such invention relates, when the foregoing description has been carefully read in connection with the accompanying drawings.

Having described the invention, I claim:

A pocket case as herein described, comprising a sheet of pliable material, designed to be folded upon itself to provide a front and a back, a metal strip disposed transversely at the folded portion of the sheet for spacing the front and the back, said plate having its ends bent over the folds of the sheet, and providing a means whereby sheets, approximately corresponding to the width and length of the front and back may be secured to the case; said front and back, at their outer ends having substantially rectangular metal frames fixed thereto and the corners of the frames being extended for contacting engagement to hold the front and back spaced from each other for a distance approximately equaling the width of the plate.

In testimony whereof I affix my signature.
CARL MARCH.
